(No Model.)

T. WILLARD.

ROCK AND COAL DRILL.

No. 323,007.

Patented July 28, 1885.

UNITED STATES PATENT OFFICE.

THOMAS WILLARD, OF WOODVILLE, PENNSYLVANIA, ASSIGNOR OF TWO-
THIRDS TO JOHN A. HARTZ AND ENOCH P. HOLLAND, OF SAME PLACE.

ROCK AND COAL DRILL.

SPECIFICATION forming part of Letters Patent No. 323,007, dated July 28, 1885.

Application filed November 20, 1884. (No model.)

To all whom it may concern:

Be it known that I, THOMAS WILLARD, of 5
Woodville, (Colliertownship,) in the county of
Allegheny and State of Pennsylvania, have
invented a new and useful Improvement in
Rock and Coal Drills; and I do hereby declare
the following to be a full, clear, and exact de-
scription thereof.

My invention relates to the drills employed
10 in mines and quarries for drilling for blasting
purposes; and it has special reference to the
drills employed in mines for ore and coal, its
object being to provide a light, efficient, and
durable drill, one which is not too heavy to
15 be carried by the miner, and which, if left in
the mine, will have its principal parts pro-
tected from rust, as well as to do away with
the frames heretofore generally employed with
these mining-drills, and provide a drill which
20 can be employed close to the floor, roof, or
walls of the mine.

It has special reference to that class of drills
in which the screw-shaft is inclosed within a
tube, the end of which fits against the walls
25 of the mine or other support, and so supports
the drill, as shown in patent to J. H. Fergu-
son, March 29, 1881, No. 239,324. It also re-
lates to certain improvements in the feeding
mechanism, whereby the feeding-nut, through
30 which the screw-shaft passes, may be rotated
in the same direction, but at a less speed than
the screw-shaft, thus obtaining a much slower
feed relative to the speed of the drill than can
be obtained when the nut is stationary, in or-
35 der to apply the advantages of the apparatus
shown in patent to J. North, December 24,
1872, No. 134,305, in connection with light
hand-drills. The special features of my im-
provements will be particularly set forth in
40 the specification and claims.

To enable others skilled in the art to make
and use my invention, I will describe its con-
struction and operation, referring to the ac-
companying drawings, in which—

45 Figure 1 is a face view of my improved
drill, illustrating its use where it is supported
by the shoe at the end thereof. Fig. 2 is a
side view illustrating its use where it is sup-
ported by an adjustable claw. Figs. 3 and 4
50 are longitudinal central sections through the
screw-shaft at right angles to each other. Fig.

5 is a longitudinal section of the partible nut
and bevel-pinion for rotating it. Fig. 6 is a
back view of the operating bevel-wheels; and
Fig. 7 is a view of the adjustable claw.

Like letters of reference indicate like parts
in each.

The drill is formed generally of the screw-
shaft *a*, the inclosing-tube *b*, the rotating nut
c, and bevel-gear for rotating the shaft *a* and 60
nut *c*. The screw-shaft is provided with a
heavy thread extending from one end to the
other, the shaft being generally tapped with
four threads to the inch in these rock and coal
drills, and this heavy thread being stronger 65
and less liable to injury than the usual thread
of ten threads to the inch generally employed
on the screw-shafts of coal-drills. At one end
of the shaft *a* is the socket *a'* to receive the bit
a'', which is held therein by a set-screw. The 70
screw-shaft is inclosed in the tube *b*, which is
of sufficient length to receive the shaft, thus
inclosing it and protecting it from injury from
blows and at the same time preventing contact
of the sulphur-water dripping from the walls 75
or lying in pools in the mine with the threads
of the shaft. As this sulphur-water might
enter through the end of the tube, I have
filled the tube with oil, thus surrounding the
screw-shaft with a fluid which will protect it 80
from the water and prevent its rusting, and
at the same time keep it lubricated for use.
The oil is retained within the tube by the
washer *b'*, fitting tightly around the screw-
shaft at the base of the enlargement *b'* of the 85
tube. The screw-shaft has a keyway, *d'*, ex-
tending from end to end, and fitting around the
shaft is the bevel-pinion *d* having a key or
feather, *d''*, fitting in the keyway *d'*. This
pinion *d* is journaled in one arm, *e'*, of the 90
frame *e*, said frame having the arm *e'*, provided
with a sleeve fitting around the tube *b* and se-
cured thereto by the set-screw *e''*.

Fitting around and engaging with the screw-
shaft within the frame *e* is the nut *c*, which is 95
preferably made partible so that it may be
opened and allow of the sliding of the screw-
shaft through it, thus permitting of the rapid
adjustment of the drill to the proper length
for drilling purposes. The nut *c* is secured to 100
the bevel-pinion *f*, which fits around the screw-
shaft, and, when partible, the two parts or

halves of the nut are hinged or pivoted to the annular ring f' of the pinion, the hinge-lugs of the nut fitting in the recesses in said ring, which thus forms a support around the screw-shaft for the partible nut. The two parts or halves of the nut are held in engagement with the screw-shaft by the enlargement or extension b' of the tube b , which fits around the nut against the ring f' of the pinion, the base of the nut pressing against the washer b^2 . The nut is opened, to allow of the sliding of the screw-shaft through it, by loosening the set-screw e^3 and sliding the frame e along the tube and shaft until the extension b' is drawn off the nut, as shown in Fig. 3, and when the drill is adjusted to place, the nut is closed, the frame drawn down until the extension b' passes over the nut, and the parts secured in position by the set-screw. Both the pinion d and the pinion f are rotated, the pinion d at a greater speed than the pinion f , according to the feed desired, as it is evident that where the shaft and the nut around the shaft are rotated in the same direction the feed depends on the relative speeds of the shaft and nut. Power is applied to these pinions d f through the combined bevel-pinion h , mounted on the shaft i , journaled in the frame e , the shaft being rotated by the handle k . The combined bevel-pinion is formed in two parts, the main portion l being rigidly secured to the shaft i and having two geared or toothed faces, l l' , which mesh with the pinion f according to the relative speed at which it is to be rotated, and the concave face m in the center of the pinion within which the pinion f rests when it is desired to give the screw-shaft its full feed of an inch on every four revolutions, as in drilling clay, the nut and its pinion f being then held from turning by a set-screw passing through the extension b' and holding the nut. Fitting around this pinion l is the pinion n , which meshes with the pinion d , the pinion n being formed of an annular ring having an inner flange, s , fitting back of the geared face l' of the pinion l , and held in place by the plate p , secured on the back of the pinion l , thus forming an annular seat for the pinion n . In the flange s are one or more slots or seats, s' , with which the pawl s^2 on the pinion n engages, this pawl being controlled by a set-screw, so that the pinions l and n may rotate together, or when the pawl s^2 is withdrawn the pinion l rotate separately, the purpose being to provide means for rapidly advancing or withdrawing the screw-shaft and bit by turning the nut c around the screw-shaft while the shaft is not rotated, the shaft being withdrawn when the nut is turned to the right, and being advanced when the nut is turned to the left, the weight of the shaft and its friction on the walls of the hole drilled holding it from turning.

To support the drill and take the thrust in drilling, the tube is provided with the shoe r , which is rigidly secured thereto, and has the beveled face r' , so that it may obtain a strong

hold on the floor or side walls of the mine or against the post, wagon, or other support employed to take the thrust. As in drilling along the side walls of the mine and in other positions it is sometimes impossible to support the drill by the shoe r , I have employed a claw, t , for use in such positions, the claw having three or more fingers and being adapted to catch upon an object at the side of the tube, as, for example, within a groove cut in the wall of the mine, as shown in Fig. 2, or against a post or other support in the mine. The claw t is secured to the tube b by means of the set-screw t' .

The operation of the drill is as follows: When it is desired to employ the drill in a position where it can be supported by the shoe r at the end of the inclosing tube b , the partible nut c is opened and the screw-shaft a drawn out until the bit is drawn in contact with the rock or coal to be drilled. The nut is then closed upon the screw-shaft and slipped into the extension b' of the tube b , and the frame e secured to the tube by the set-screw e^3 when the drill is in position for use. Instead of opening the nut, the pinions l and n may be disengaged, and the screw-shaft will be advanced rapidly by turning the pinions l and f to the left, thus screwing out the shaft. In drilling, the pinions l and n being connected by the pawl s^2 , the operator turns the handle to the right, and through the pinions n and d he rotates the screw-shaft, causing it to advance at the rate of one-fourth inch on each revolution where the nut c is not rotated. As, however, the pinion l meshes with and rotates the pinion f , and the nut c secured thereto in the same direction as the screw-shaft, the screw-shaft is only advanced in proportion to the relative speeds of the shaft and the nut, so that I obtain the advantage of a rapidly-rotating and slowly-advancing drill, and at the same time employ a screw-shaft having a heavy and strong thread. The feed of the drill depends, in the apparatus shown, upon the gear-face l' or l^2 , with which the pinion f engages, the gear-face l' having a greater number of teeth and consequently rotating the pinion and nut at a greater speed relative to that of the shaft. In the drill, in use, the pinion d and shaft a rotate twenty-three times while the pinion f and nut c are rotated nineteen times by the gear-face l' , it thus requiring twenty-three revolutions of the shaft to gain the four threads necessary to feed the shaft forward one inch, and the pinion d and screw-shaft rotate ten times while the pinion f and nut are rotated six times by the gear-face l^2 , thus requiring ten revolutions of the shaft to gain the four threads necessary to feed it forward one inch. The former feed may be employed for drilling hard rock and ore, while the latter is suitable for drilling coal. After the hole is drilled to its full depth, the operator disengages the pinions l and n , and can draw the drill out rapidly by turning the nut c to the right, the drill being

withdrawn at a speed of four revolutions to the inch. He can also withdraw it by drawing back the bit a short distance by means of the gearing and then loosening the set-screw 5 e^3 and sliding the frame on the tube until the partible nut can be opened, when he can slide the screw-shaft back into the tube.

The pinion f may be caused to mesh with either gear-face l' or l^2 , or be placed in the 10 space m in the center of the wheel, so that it remains stationary, by opening the partible nut drawing the screw-shaft out of the tube, and, after placing the pinion in the position desired, replacing the screw-shaft.

15 The shoe r supporting the drill may be placed against the floor, wall, roof, any post, or even against the coal-car when in a convenient position.

If the shoe cannot be conveniently used to 20 support the drill, the claw t may be employed, its fingers holding within a slot in the wall or any other support to take the thrust.

The drill may be employed at any angle 25 and as close as desired to the floor or walls, as illustrated in the drawings.

The claw t is found advantageous in drilling deeper holes than the length of the screw-shaft allows, as it may be secured close to the frame e and the hole drilled part way, and the 30 drill then withdrawn and the tube pushed forward through the claw, which is secured close to the other end, and the drilling continued. This is of great advantage in tunneling.

35 I am thus enabled to provide a hand-operated screw-drill for rock-drilling purposes in which the feed may be regulated according to the character of the work, and which can be operated in any desired position. The drill 40 is light, not weighing over thirty pounds, so that it can be carried by the workmen. I also obtain a slow feed from a screw-shaft having a heavy, strong thread, which is not so liable to wear or injure it, and protect the 45 screw-shafts from the injurious effects of the sulphur-water of the mines, so that it could remain in the mine for six months without injury. I also keep the screw-shaft constantly lubricated, and so prevent wear.

50 I am aware that partible nuts have heretofore been employed with rock-drills, and hence do not claim the same, broadly; but these partible nuts were hinged at the side, and hence required a separate support from 55 the screw-shaft, whereas by hinging the nut

at the end I am enabled to support it on the screw-shaft, and it is more easily opened to allow the sliding of the screw-shaft.

What I claim as my invention, and desire to secure by Letters Patent, is—

1. In combination with the drill and screw-shaft and the inclosing-tube, the partible nut hinged at its end to its support around the shaft, and means for holding it in engagement with the shaft.

2. In combination with the drill and screw-shaft, the partible nut c and the tube b , having the extension b' fitting around the nut, substantially as and for the purposes set forth.

3. In combination with the drill and screw-shaft, the support b , the sliding frame e , having a collar fitting around said support and secured thereto by a set-screw or equivalent device, partible nut c , engaging with the shaft within the frame, and the extension b' 75 on said support fitting around said nut, substantially as and for the purposes set forth.

4. In combination with the drill and screw-shaft, the support b , having the extension b' , the frame e , adjustably secured to said support and carrying the pinion l , and the pinion f and partible nut c hinged thereto and engaging with the screw-shaft within the frame, substantially as and for the purposes set forth.

5. The combination of the drill and screw-shaft, the support b , having the extension b' , frame e , adjustably secured to the support and carrying the pinion d keyed to the screw-shaft, pinion f , carrying the partible nut c , engaging with the screw-shaft, combined power-pinion h , mounted in the frame and formed of the pinion l and ring-pinion n around it, and means for connecting the two pinions, substantially as and for the purposes set forth.

6. In combination with the drill and screw-shaft, the pinion d , keyed thereto, the pinion f , carrying the nut engaging with the shaft, the combined pinion h , having the ring-pinion n meshing with the pinion d , and the pinion l , having two gear-faces, l' l^2 , to mesh with the pinion f according to the feed desired, substantially as set forth.

In testimony whereof I, the said THOMAS WILLARD, have hereunto set my hand.

THOMAS WILLARD.
